K. LEHPAMER

LATH

Filed Jan. 31, 1925

Karl Lehpamer
INVENTOR
BY Frank Schaefer
ATTORNEYS.

UNITED STATES PATENT OFFICE.

KARL LEHPAMER, OF CICERO, ILLINOIS.

LATH.

Application filed January 31, 1925. Serial No. 5,975.

To all whom it may concern:

Be it known that I, KARL LEHPAMER, a citizen of the United States, residing at Cicero, in the county of Cook and State of Illinois, have invented new and useful Improvements in Laths, of which the following is a specification.

This invention relates to improvements in lath and has particular reference to metal lath such as used for retaining plaster on wall and ceiling of structures, dwellings and the like.

The invention contemplates also an improved metal lath which shall be particularly adaptable for use in retaining cement coverings, such as "stucco" for exterior wall finishes on buildings and structures of various kinds.

Among the objects of the invention is the provision of a metal lath of the above character which shall be of such configuration in cross section that the plaster or cement retained thereby shall not only be keyed or anchored within the laths but shall also be keyed or locked within the spaces between the laths.

With these and other objects in view, my invention consists in the novel combination and construction of the various portions of the lath as shown on the accompanying drawing, described in the following specification and particularly pointed out in the appended claim.

Referring to the illustration, Figure 1 is a plan view of a lath embodying my invention. Figure 2 is a cross section of same taken on line 2-2 of Fig. 1, and Figure 3 an illustration in cross section of a plastered

wall showing the application of my lath and the "keys" or "locks" formed by the plaster between and within the laths.

Referring to the illustration, 10 indicates the bottom of my improved lath which is formed with integral sides 11 extending longitudinally thereof. The sides 11 are angularly disposed with relation to the bottom 10 and bent outwardly away from each other. The upper end portions 12 of the sides 11 are bent toward in reverse direction, or rather toward one another and substantially parallel to the bottom 10.

In use, the laths are secured by nails on the supporting sheathing 13 or may be placed directly on the studding 14. The space between the laths may be varied to suit the plaster material.

It will now be readily apparent by reference to the cross section in Figure 3, that the plaster 15 not only forms a "lock" or "key" between the angularly bent sides 11 of the adjacent laths, but that the plaster is securely keyed in each lath and within the bent end portions 12 of the sides.

I claim:

A metal lath comprising a solid bottom portion with spaced openings therein for means for securing said lath to a structure, sides integral with said bottom portion extending longitudinally of said bottom portion and being bent at an angle thereto and outwardly from the longitudinal center line of said bottom, said sides having their outer portions bent angularly toward each other and parallelly with said bottom.

In witness whereof I affix my signature.

KARL LEHPAMER.
